UNITED STATES PATENT OFFICE.

ADOLF LEINWEBER, OF MUNICH, GERMANY.

CASTING-MACHINE.

1,189,976.

Specification of Letters Patent.

Patented July 4, 1916.

Application filed November 19, 1912. Serial No. 732,289.

To all whom it may concern:

Be it known that I, ADOLF LEINWEBER, a subject of the Emperor of Germany, and residing at Munich, Bavaria, Germany, have 5 invented certain new and useful Improvements in Casting-Machines, of which the following is a specification.

In the art of casting the printing plates for rotary printing presses there are known 10 among other casting machines also such in which the liquid metal is forced from the melting pot into the mold, by means of a piston pump. These casting engines do not allow of an economical working, and they 15 are, furthermore, subject to too great a wear and tear, especially with regard to the melting pot.

The objects of the present invention are first, to do away with these drawbacks, and 20 second, to produce a machine which is able to cast the plates quickly and without danger, although there is but one pump employed, without any turning or swinging device. This novel machine is also very durable, as well as simple. It is provided with 25 distributing pipes, which are arranged at the two sides of a hand pump located in the melting pot, which is of a corresponding width and increases gradually in depth from 30 the place of introduction of the metal to be melted. Said pipes are connected with said pump one after the other, which may be controlled from the molds by the opening and closing of their (preferably balanced) 35 covers or lids.

In order to make my invention more clear, I refer to the accompanying drawings in which similar letters denote similar parts and in which—

40 Figure 1 is a longitudinal section through my improved casting machine; Fig. 2 is a plan of same; Figs. 3 and 4 show a cross section and a longitudinal section through the distributing pipes; Fig. 5 is a detail view partly in section of the spring actuated racks and the lever system operating the same. Fig. 6 is a section on the line A—B of Fig. 5. Fig. 7 is a section on the line C—D of Fig. 5. Fig. 8 is a detail view of the pointer and the 45 notches receiving the same during the rotation of the slide. Fig. 9 is a detail view of the system of levers for actuating the racks. Fig. 10 is a side view, partly in section of the bevel wheel gearing operating the sleeve-axle 50 for the bell-crank levers. Fig. 11 is a detail view of one of the releasing levers. Fig. 12 is a diagrammatic view of the pointer arrangement.

The melting pot *a*, the bottom of which is inclined from the charging place *b* to the opposite end, contains a hand pump *c*, the piston of which is provided in the usual manner with piston rings and a return valve, and is moved up and down by means of a hand lever. These details of the pump are 60 but partly represented, because they are known and of no particular significance. The pump is connected at its side or sides with one or more distributors *d*, each of which terminates in an upward direction in 65 a plurality of distributing pipes, for instance three, such as *e*¹, *e*², *e*³ (Fig. 3). Each of these pipes leads to a mold and serves to fill the latter with molten metal from the melting pot. The construction of the mold 70 17 and the manner of leading the distributing pipes *e*¹, *e*², *e*³ to the same is clearly illustrated in Fig. 1. Each of the molds consists of a suitable frame carrying a trough 75 18 removable cheeks 19 and a core *x* fulcrumed at *v* and provided with a counterweight *w*. The rear wall 21 of the mold 17 extends above the trough 18 and forms together with the tongue- or bill-shaped extension 22 and the cheeks 19 of equal height, a 80 funnel which leads to the mold proper. A matrix is introduced into the mold 18, whereafter the lateral cheeks are mounted so as to overlap the lateral edges of the said matrix securing the same into place. Hereafter, the 85 core *x* is introduced by turning it around its fulcrum *v* and then the mold is ready to be charged with the mold metal carried from the melting pot by the distributing pipes 90 *e*¹, *e*², *e*³. The pipes *e*¹, *e*², *e*³ branch off from the distributor in the same plane and in the plane of a common rotary slide *g* (Figs. 3 and 4) provided at said places. While the parts are in their normal positions, the opening *h* of the slide *g* is closed and is located 95 below the places *f*¹, *f*², *f*³ where the distributing pipes *e*¹, *e*², *e*³ branch off. In order to admit the molten charge to one of the pipes, the slide must therefore be raised. This is effected by hand. By turning the slide the 100 same is brought into communication with any one of said distributing pipes. This is automatically effected during the introduction of one of the cores *x* into its mold, as the arm of this core carrying the counterweight *w* effects, as stated above, a displacement of the corresponding rack *l*¹, *l*², *l*³, 105 110

which rotates the rod or shaft *i* carrying the slide *g* until it is again put out of action by the roller *p*¹ which is arranged at the side of the toothed wheel *k* corresponding to said rack.

The three rollers *p*¹, *p*², *p*³ are in the same manner distributed in a circle as the branching places *f*¹, *f*², *f*³ and three positively coupled toothed wheels *k*¹, *k*², *k*³ are correspondingly distributed, or in other words: for each toothed wheel a roller is provided and the rollers are positioned with respect to each other in such a manner that if projected upon a plane vertical to the shaft of the toothed wheels *k*, their axes fall upon three lines dividing a circle into three equal segments, the center of which is formed by the point of intersection of said three lines. Therefore, the core of the mold 21¹ will always bring the opening *h* in communication with the branch *f*¹ of the distributing pipe *e*¹. After the mold has been charged the slide is returned into its lowermost position. After the mold has been filled the communication is interrupted automatically or by hand by an axial displacement of said slide.

In order to actuate the slide for operating in the described manner, it is firmly connected with a rotary rod *i*, which is connected with as many rack gears *k*¹, *k*¹, *k*², *k*², *k*³, *k*³, as there are distributing pipes connected with the distributor, and which is also connected with a hand lever *m* having its fulcrum at *n* and which is secured in its two end positions by a leaf spring *o*, provided with a handle which has suitable notches for the reception of said lever *m*.

The rod *i* stands under the influence of a spring 13, which, when a mold is opened or closed after the spring *o* has released the lever *m*, depresses the rod into a position in which all distributing pipes are closed. The release of the arm *m* is effected upon the opening or closing of a mold, as will be more fully described hereinafter.

The cog wheels *k*¹, *k*², *k*³ are longitudinally displaceable upon the rotary connecting rod *i* and they are provided with lateral rolls or lugs *p*¹ which interrupt the connection between the racks *l*¹, *l*², *l*³ and the cog wheels *k*¹, *k*², *k*³ by lifting the former as soon as that rack gear, which has been actuated on the closing of a mold, has turned the rod *i* far enough to adjust the exit opening *h* of the rotary slide in proper position to the entrance of the respective distributing pipe *e*¹ or *e*² or *e*³. The racks *l*¹, *l*², *l*³, which are preferably acted on by springs 14 are operated by means of a system of levers (in the direction indicated by the arrow in Fig. 5) which also moves the racks back into their former position when the mold is opened, as is also more fully described hereinafter. When thus being moved the racks *l*¹, *l*², *l*³ are brought by the

lugs *p* into the range of action of catching arms *q*¹, *q*², *q*³ (Fig. 7), which prevent the racks when returning to come into gear with the respective cogwheels, so that consequently the rotary slide remains unaffected. 70 In the sectional drawing (Fig. 7) for instance the middle rack *l*² is shown lifted and caught or checked by the arm *q*².

The system of levers for actuating the racks *l*¹, *l*², *l*³ as shown in Figs. 1 and 9, 75 consists of bars *t*¹, *t*², *t*³ provided with lugs *r* and *s* and of a bell crank lever *u* the arms *u*¹, *u*², *u*³ coating with the racks *l*¹, *l*², *l*³ and the bars *t*¹, *t*², *t*³ respectively. The lugs *r* and *s* are so arranged with respect to the core *x* of the mold, which may be turned around the hinge *v* and is furnished with a counter poise *w*, that when opening the mold the cover presses from above upon the upper lug, whereas when closing the mold 85 the lower lug is acted on by the counter poise mentioned. In this manner the racks *l*¹, *l*², *l*³ are moved when the mold is closed by the core *x* in the direction of the arrow Fig. 5, while before and during the closing 90 of said mold they are returned to their initial position.

Fig. 9 shows the parts when the core *x* is opened, and the corresponding position of the coöperating parts *t*, *u* is represented in 95 full lines, whereas the other position is indicated by dotted lines.

Each of the bell-crank levers *u*¹, *u*², *u*³ is furthermore provided with an arm or a projection *z* which is adapted to release the 100 checking part *o* of the lever *m* upon the raising, as well as lowering of the bar *t*; that is to say, when the mold is closed and re-opened; said releasing action may be effected, for instance, by the mediation of a lever 105 2, which laterally engages said projection.

If there are arranged distributing pipes at both sides of the pump, then the rotary slide belonging to the other pipes is actuated in exactly the same manner as just described. It is in such a case advantageous to couple the two releasing levers 2 with each other, for instance, by means of a rod 3 (Fig. 9) so that the rotary slide of the one side, in the case of having inadvertently 115 remained open, is automatically released and caused to return into the other position by the releasing of the rotary slide of the other side, *i. e.* before the pump commences to work again. 120

As all racks are in juxtaposition, whereas the molds coöperating with one and the same rotary slide are some distance from each other and are furthermore, generally distributed upon two sides of the melting pot, the arrangement of the arms of the bell-crank levers as shown in Fig. 9 cannot, of course, be employed without a proper adaptation and besides, attention must be paid to the fact that each arm of the bell-crank 130

levers remains movable *per se*, independent of the other ones. This may be attained by any desired means.

In order to positively guide the rotary slide into its proper position with respect to the mold to be filled, there may be arranged upon the axle in question an elastic pointer 12 (Figs. 6 and 8), which snaps into one or the other of a plurality of notches 15 during the turning of the slide. These notches are designated by numbers in the same manner as the molds or are otherwise suitably marked. The elastic pointer entering the notches serves also for securing the slide *g* in its place, *i. e.* for preventing its accidental displacement.

The machine operates as follows: The position of the rotary slide *g* at the beginning of the work is such that the distributing pipes *e* are closed against the pump, and that no metal can escape from the melting pot to the mold even if the pump is erroneously actuated as the slide at the time in question, is below the branching places *f* of said pipes. Of the molds at disposal any one may be used in the beginning and the other ones may be employed in any desired succession, because each mold has a separate connection of its own (bell-crank rods and rack gear) with the rotary connecting rod *i*. The matrix is placed into the respective mold in known manner and thereafter that mold is closed. When closing the mold, the cover or core *x* by its weight in the manner before described, forces the corresponding bar *t* upward whereby the bell-crank lever connected with said bar is turned into position indicated by dotted lines in Fig. 9. By this means the rotary slide *g* is turned so as to adjust it with regard to the respective distributing pipe, for instance, *e*¹. At the same time the corresponding rack for instance *l*¹, has been moved in the direction of the arrow (Fig. 5) and after it has sufficiently turned the bar *i*, it is raised by the projection *p*¹ of the corresponding cog wheel *k*¹ so as to come out of action. It is now grasped by the catch arm *q*¹ and retained in that position. At the same time the lug *z* slips below the nose of the lever 2, without any change in the position of the bar *i*, but the connecting rod of the other distributing pipe is released in consequence of its positive connection with the other distributing pipe, so that it is allowed to drop into its general locking or closing position, if it was raised. As soon as the controlling pointer 12 is in its proper position, the bar *i* is drawn upward, against the action of the spring 13, until it is automatically locked in its raised position by means of the locking device *o*. Thereafter the pump is operated until the mold has been properly charged. The other molds are filled with the molten metal in

exactly the same manner. In the meantime the metal in the first mold has cooled down so that this mold can be opened. To this effect, first the locking device *o* is released by means of the projection *z*, so that the rod *i* is forced downward by the spring 13 (Fig. 1) and closes the inlet to all distributing pipes. At the same time, *i. e.* simultaneously with the lifting the mold cover, the corresponding racks *l*¹, *l*², *l*³ are moved into their initial position by the mediation of the respective rods, but the racks cannot turn the cog wheel *k*¹ or the connecting rod *i*, respectively, because they are prevented from such action by the catching arms *q*¹.

The racks *l*¹, *l*², *l*³ and the cog wheels *k*¹, *k*², *k*³, the springs 14, and the catching arms *q*¹, *q*², *q*³ may be inclosed in a suitable casing, for instance, such as 16.

If distributing pipes *e*¹, *e*², *e*³ are connected with the pump at both sides of the latter, the manner of operation upon the other side is just the same as before described.

What I claim as new and desire to secure by Letters Patent is:

1. In a casting machine provided with a hand pump in combination, a melting pot within which said pump is arranged, a plurality of molds adapted to be charged with the molten metal from said melting pot, distributing pipes connected to said pump, means for distributing the molten metal into said pipes for discharging it into said molds, means between said pipes and the distributing means for operating the distributing pipes in harmony with the opening and closing of the corresponding molds, and means for actuating said operating means upon the introduction of a core into a mold, substantially as described.

2. In a casting machine provided with a hand pump, in combination, a melting pot within which said pump is arranged, a plurality of molds adapted to be charged with the molten metal from said melting pot, a distributor for said metal connected to the sides of said pump, distributing pipes connected to said pump into which said metal is distributed, a rotary slide between said distributor and said pipes, means for operating said slide to distribute the metal from said distributor into said pipes in harmony with the opening of said molds, substantially as described.

3. In a casting machine provided with a hand pump, in combination, a melting pot adapted to receive said pump, a plurality of molds in juxtaposition to said pot, adapted to be charged with the molten metal from the same, distributors laterally arranged upon said pump, distributing pipes connected with said pump into which said metal is distributed, a rotary slide provided with an opening and arranged between said dis-

tributers and said pipes, means for operating said slide to close said distributing pipes, means for operating said slide for distributing the metal from said distributor into said pipes, a counter-balanced core within each of said molds for operating said slide operating means upon the introduction of said core for distributing the molten metal into one of said pipes and into said mold, substantially as described.

4. In a casting machine provided with a hand pump within the melting pot thereof, a plurality of molds in juxtaposition to said pot adapted to be charged successively with the metal from said pot, distributing means for distributing the charge contained in said pot, comprising distributor and distributing pipes, a rotary slide provided with an opening arranged between said distributor and said pipes, a rotary rod connected to said slide, rack gears and a system of levers for rotating said rod, means for operating said levers upon the operation of a core for adjusting the opening of said rotary slides to communicate with one of the distributing pipes, means for locking said rod in this position, and means for releasing said rod for dropping said slide into its position for locking said distributing pipes, substantially as described.

5. In a casting machine of the character described a melting pot, a hand operated pump within said pot, distributor radially disposed to said pump, distributing pipes connected to said pump, a rotary slide provided with an opening and arranged between said distributor and said pipes, molds in juxtaposition to said pot, means for rotating said slide upon the operation of the

core of one of said molds for forming a communication between the distributor, one of the distributing pipes and said mold, means for locking said slide in this position, and means for returning said slide into its position interrupting the communication between said distributing pipes and said distributor at the end of the charging period for said molds, substantially as described.

6. In a casting machine of the character described, a melting pot, a hand operated pump within said pot, distributor, laterally disposed to said pump, distributing pipes connected with said pump, a rotary slide provided with openings and arranged between said distributor and said pipes, molds in juxtaposition to said pot, counter-balanced cores for said molds, a rotary sliding rod carrying said slide, means for normally holding said slide in its lower position for interrupting the communication between said distributor and said pipes, means operated by the operation of one of said cores for raising said slide to establish a communication between said distributor and one of said distributing pipes corresponding to the mold the core of which has been operated, means for locking the parts in their respective positions during the charging period, and means for operating the slide returning means after the mold has been charged, substantially as described.

In testimony whereof I affix my signature in presence of two witnesses.

ADOLF LEINWEBER.
